P. G. MacGREGOR

FIRE EXTINGUISHER

Filed Oct. 6, 1925

UNITED STATES PATENT OFFICE.

PETER G. MACGREGOR, OF PEQUANNOCK, NEW JERSEY, ASSIGNOR TO PYRENE MANUFACTURING COMPANY, OF NEWARK, NEW JERSEY, A CORPORATION OF DELAWARE.

FIRE EXTINGUISHER.

Application filed October 6, 1925. Serial No. 60,708.

This invention relates to fire extinguishers and is herein shown embodied in a fire extinguisher of the portable type, comprising a liquid receptacle within which is arranged a double acting pump adapted to forcibly eject the liquid from the receptacle on both the inward and outward movements of the piston, regardless of the position in which the extinguisher is held.

10 In extinguishers of the type mentioned it is customary to provide a nozzle tube located centrally of the piston tube or piston operating member to which an operating handle is connected, the handle being provided with 15 means for locking it, when not in use, to the extinguisher head through which the piston tube reciprocates and through which air is admitted around the piston tube as the liquid is expelled during operation of the extinguisher.

Heretofore a compressible packing carried by the operating handle has been employed as a means for sealing around the piston tube the space through which air 25 is admitted to the receptacle as the liquid is displaced. The packing so employed has been forced into intimate engagement with the extinguisher head upon locking the handle to the receptacle, but it has been found 30 that after a time the packing becomes reduced in thickness to such an extent that the handle, in the absence of means adapted to compensate for the reduction in thickness of the packing, fails to so cooperate with the 35 packing as to effectively seal the space afforded between the piston tube and the extinguisher head.

One of the objects of the invention is to overcome the objection above mentioned, and 40 to this end a compensating means is provided which is so associated with the operating handle as to maintain the packing in intimate engagement with the extinguisher head when the handle is locked to the extinguisher and thereby maintain an effective seal around the piston tube.

Another object of the invention is to provide an improved means for sealing the inlet end of the nozzle tube when the handle is locked to the extinguisher.

A further object of the invention is to provide an improved means, surrounding the piston tube intermediate the pump cylinder and the extinguisher head, for removing the film

of liquid from the piston tube on its outward stroke and thereafter diverting such liquid back into the liquid supply.

Another object of the invention is to provide an improved means for restraining the flow of liquid from the receptacle through the space afforded between the piston tube and extinguisher head without unduly obstructing the passage of air into the receptacle through the space afforded between the piston tube and extinguisher head while the extinguisher is being operated.

Other objects and certain advantages of the invention will become apparent from the following description when taken in connection with the accompanying drawings in which—

Figure 1 is a longitudinal, central sectional view through an extinguisher embodying my invention.

Figure 2 is an end view of the inwardly projecting portion of the piston head constituting an element of a breather.

Figure 3 is a perspective view of a stripper element.

Figure 4 is an enlarged fragmental central sectional view through the piston tube and the nozzle tube showing the position of the nozzle tube valve when the handle is locked to the extinguisher head.

Figure 5 is a view in elevation of the upper pump head.

Figure 6 is a view in elevation of the lower pump head.

Figure 7 is a sectional view taken on line 7—7 of Figure 8.

Figure 8 is a sectional view taken on line 8—8 of Figure 5.

Figure 9 is a sectional view taken on line 9—9 of Figure 6.

Referring to the drawings, the numeral 10 indicates a double acting pump arranged within a liquid receptacle 11 which is provided with a head 12 to which an operating handle, 13, for the pump 10, is adapted to be locked when the extinguisher is not in use.

The pump 10 comprises a pump tube 14, to opposite ends of which are secured pump heads 15 and 16 formed respectively with offset portions 17, 17' and provided with inlet ports 18, 18' and valve chambers 19, 19' respectively. Within the valve chambers 19, 19' are valves 20, 20' connected together by means of a rod or link 21 which extends through a tube 22 suitably connected with the

offset portions 17, 17' and maintained in communication with passages 23, 23'. The passages 23, 23' are adapted to communicate with the valve chambers 19, 19' and are also 5 adapted to communicate with ports 24, 24' which lead to valve chambers 25, 25' adapted to communicate respectively with opposite ends of the pump tube 14 through ports 26, 26'. Valves 27, 27' are arranged within the 10 valve chambers 25, 25' respectively, the valves 27, 27' being adapted to cooperate with their respective seats, at the inner ends of the chambers 25, 25' to sever communication between the ports 24, 26 and the ports 24', 26'. 15 The valve chambers 25, 25' and also the valve chambers 19, 19' are closed by means of discs 28, seated upon the outer ends of ribs or guides 29 which serve to maintain the valves 27, 27' and 20, 20' centrally located within 20 their respective chambers.

Within the pump tube 14 is arranged a piston operating member, herein shown as a piston tube 30, which projects through the head 12 and carries at its inner end a piston 31. The piston 31 is movable upon the piston tube 30 and is adapted to so move, when the piston is thrust inwardly, as to open inlet ports 32 and close inlet ports 33 formed in the piston tube. Upon reverse movement of 30 the piston tube 30 the piston 31 so moves as to close the inlet ports 32 and open the inlet ports 33, the piston 31 being limited in its movement in one direction by a collar 34 carried by the piston tube and limited in its 35 movement in an opposite direction by means of a gland nut 35 carried at the end of the piston tube and provided with a packing 36 surrounding a nozzle tube 37. The nozzle tube is arranged centrally of the piston tube 30 and is secured in position by reason of its connection with a nozzle 38 which is secured to the outlet end of the receptacle 11.

The pump heads 15 and 16 are preferably die cast, and in order that they may be interchangeable and in order that a single die may be employed for both heads, they are identical, each being formed centrally with an opening 39 which is sufficient in diameter to receive the piston tube 30, but oversized with 50 respect to the nozzle tube 37. This oversize, however, may be taken care of by means of a bushing 41 positioned within a pocket 42, the bushing 41 being provided with a packing material 43 over which is positioned a 55 retaining plate or disc 44. The pockets 42 are identical in shape and dimensions, and whereas one of the pockets is adapted for the reception of the bushing 41, the other pocket is adapted for the reception of a packing material 45 which surrounds the piston tube 30 and is retained in position by means of a retaining disc 46. The retaining discs 44 and 46 are identical, except as to thickness, and are retained within their respective pockets 60 by spinning over the adjacent metal to pro-

vide retaining beads as shown at 48. It will be noted that the disc 44 is seated upon the outer end of the bushing 42 which is seated upon a ledge 49 and that the disc 46, overlying the packing 45, is seated directly upon the ledge 49, the disc 46 being somewhat thicker than the disc 44 to compensate for the thickness of the outer end of the bushing 42 as will be readily understood.

The head 12 comprises the usual lock plate 75 50, for locking the handle 13 to the head, and a sleeve 51 through which the piston tube 30 operates, the sleeve being formed at its inner end with a depending flange 52, constituting a retaining element, provided with a 80 plurality of openings 53. This retaining element is spaced from the piston tube 30 and functions as a means for retaining a packing ring 54 in position around the piston tube. Around the retaining element 52 is also carried a packing ring 55. These packing rings, together with the associated sleeve 51 and retaining element 52, constitute a breather which permits air to enter the receptacle 11, around the piston tube 30, as the liquid is 90 ejected from the extinguisher, but at the same time offers an adequate obstruction to prevent the liquid from escaping through the space afforded between the piston tube 30 and the sleeve 51.

Inasmuch as the piston tube 30 reciprocates through the head 12 it, on its outward stroke, tends to carry with it a film of liquid, and in order to remove this liquid there is provided a stripper 56 which is arranged, intermediate the pump head 15 and a washer 57 overlying the packing rings 54 and 55. The stripper 56 comprises a spider 58 which is seated upon the head 15, the spider 58 being provided with an opening through which the 100 piston tube 30 reciprocates and is formed with an inclined wall 59. By reason of the fact that the wall 59 is inclined and terminates a slight distance from the pump head 15, the liquid, adhering to the piston tube 110 30 on its outward stroke, is removed and deflected back into the liquid supply through a plurality of openings 61 formed in the spider, the space between the pump head 15 and the feather edge of the wall 59 being 115 maintained during the outward stroke of the piston tube 30 inasmuch as the spider 58 engages the depending flange 52 and the pump head 15. The spider 58 is also provided with a pocket 62 carrying a suitable packing 63, the packing being retained within its pocket by means of the washer 57 which also cooperates with the retaining element 52 to retain the packing rings 54 and 55 in their respective positions.

The handle 13 is slidably mounted upon the outer end of the piston tube 30 and is locked thereto by means of a pin 64 adapted to engage a spool 65 having screw-threaded engagement with the outer end of the piston 130

tube. The handle 13 is counter-bored to provide a chamber within which is arranged a compression spring 66, one end of which engages the handle and the other end of which engages a sealing means 67 adapted to sealing the space afforded between the piston tube 30 and the sleeve 51. The sealing means 67 comprises a sleeve 68 which is suitably connected to the piston tube 30 and is so shaped 10 at one end as to provide a sheath 69 carrying a packing material 71, preferably cork, over which is positioned a metallic washer 72 adapted to engage the outer end of the sleeve 51.

15 The relation between the spring 66 and the handle 13 is such that when the piston tube 30 is being operated the spring 66 tends to separate the handle 13 from the piston tube, but such separation is prevented by reason 20 of the engagement between the pin 64 and the spool 65 as indicated in dotted lines in Figure 1. When the piston tube 30 is moved a sufficient distance inwardly the sealing means 67 is brought into engagement with the 25 end of the sleeve 51, and upon further movement of the handle 13 into its locked engagement with the head 12, as shown, the handle 13 is permitted to move with respect to the piston tube 30, thereby moving the pin 64 30 from its dotted line position to its full line position shown in Figure 1. As a result of the relative movement afforded between the piston tube 30 and the handle 13, the spring 66 is placed under compression and functions, 35 so long as the handle 13 is locked to the head 12, to urge the piston tube 30 inwardly and at the same time urge the sealing means into intimate engagement with the sleeve 51. Should the packing material 71, due to the 40 constant pressure exerted thereupon by the spring 66, become reduced in thickness, such reduction in thickness is compensated for by the spring 66 and thus the sealing of the space afforded between the piston tube 30 45 and head 12, through which air is permitted to enter the receptacle, is always maintained, regardless of the length of time that the extinguisher may be out of use.

Not only is it desirable to maintain an 50 effective seal of the opening afforded in the head 12 through which the air is permitted to pass into the extinguisher as the liquid is ejected therefrom, but it is also necessary to seal the inlet end of the nozzle tube 37, and 55 to this end an improved valve structure 73 is provided. The valve structure 73 comprises a carrier 74 mounted within the piston tube 30, one end of the carrier being engaged by a compression spring 75 arranged within 60 the piston tube 30 and maintained in engagement with the screw-threaded end of the spool 65. The carrier 74 is provided with a sealing element 76, preferably a soft metallic substance, which is adapted to engage the inlet 65 end of the nozzle tube 37 when the handle 13 is moved to its locked position. As will be noted from Figures 1 and 4, the carrier 74 is formed with a funnel-shaped end 77, the inner wall of which is flared or tapered to facilitate proper centering of the sealing 70 element 76 upon the inlet end of the nozzle tube 37, should the nozzle tube, due, for example, to slight imperfections in assembling, fail to assume a coaxial position with respect to the piston tube 30, particularly when the 75 piston 31 is positioned as shown in Figure 1. Under operating conditions the carrying member 74 is restrained against movement, under the influence of the spring 75, by reason of the fact that its funnel-shaped end 80 77 is adapted to engage and rest upon a shoulder 78 formed within the piston tube 30. Upon movement of the piston tube 30 to almost its extreme inward position, the packing material 76 engages the inlet end 85 of the nozzle tube 37, and upon such further inward movement of the piston tube 30 as is necessary to bring the sealing means 67 into engagement with the sleeve 51, a relative movement between the carrier 74 and the 90 piston tube is effected, whereupon the spring 75 is compressed thereby urging the packing material 76 into intimate sealing engagement with the inlet end of the nozzle tube 37. After the locking engagement between 95 the handle 13 and the head 12 has been established, the compression of the springs 75 and 66 is maintained, the former serving to constantly urge the packing material 76 into intimate engagement with the inlet end of the 100 nozzle tube 37 and the latter, as above explained, serving to maintain the sealing means 67 in intimate engagement with the sleeve 51.

Upon unlocking the handle 13 from the head 105 12, the spring 66, being of a greater strength than the spring 75, so functions as to move the handle 13 outwardly upon the piston tube 30 until the pin 64 has assumed the position shown in dotted lines in Figure 1. After the 110 handle 13 has moved outwardly upon the piston tube 30, under the influence of the spring 66, a further slight movement of both the handle 13 and the piston tube 30 with respect to the carrier 74 is effected as a result 115 of the thrust exerted upon the carrier 74. Such relative movement is continued until such time as the piston tube 30 and the handle 13 have been so moved with respect to the carrier 74 that the ledge 78 engages the funnel-shaped end 77 of the carrier 74. The carrier 74, being thus seated upon the ledge 78, is lifted from the nozzle tube 37 upon the outward stroke of the piston tube 30 and remains so lifted during normal operation of 120 the extinguisher.

With fire extinguishers of the type herein shown, it is desirable that each inlet passage to the pump always assumes such a position 125 within the liquid receptacle as to insure the 130

entrance of liquid into the pump when the extinguisher is held in a horizontal position, and in order to accomplish this the pump 10 is so journaled at opposite ends as to permit the 5 pump to swing about the axis of the nozzle tube 37. The pump 10 is herein shown as journaled at one end to the nozzle tube 37 through the pump head 16 whereas the other end of the pump is journaled upon the piston 10 tube 30 through the pump head 15 the offset portions 17 and 17' of the heads 15 and 16 being of sufficient weight to insure turning of the pump 10 about the nozzle tube as an axis when the extinguisher is held in a horizontal 15 position and rotated.

When it is desired to operate the extinguisher, the handle 13 is unlocked from the head 12 by imparting to the handle a part 20 turn, as is customary, whereupon the seals afforded by the sealing means 67 and the valve mechanism 73 are broken. If the handle 13 is then drawn outward, the piston tube 30 at first moves with respect to the piston 31, thereby closing the ports 32 and opening the 25 ports 33. If the extinguisher is being operated with its nozzle 38 pointed generally downward, the liquid will enter the port 18', pass around the unseated valve 20' into the passage 23' and thence around the valve 27' 30 Figure 9 and into the lower part of the pump through the port 26'. Upon reverse movement of the piston tube 30, the piston tube 30 moves with respect to the piston 31 thereby closing the ports 33 and opening the ports 32, 35 whereupon the liquid previously drawn into the pump 10 passes through the ports 32 into and upwardly in the piston tube 30, past the unseated sealing element 76 and on into the nozzle tube 37 from which it is ejected. 40 As the piston tube 30 moves inwardly, the valve 27' closes the communication previously afforded between the receptacle 11 and lower part of the pump through the head 16. While the piston 31 is being moved inwardly, liquid is drawn through the port 18' and 45 passes up through the tube 22, from which it enters the passage 24 and passes around the valve 27 into the pump 10 through the port 26. On the next outward stroke of the piston tube 30, liquid enters the lower end of the 50 pump 10, as previously explained, and the liquid which has been drawn into the pump 10 through the head 15 passes from the pump tube 14 through the openings 33, into the piston tube 30 from which it is directed into the nozzle tube 37 and expelled.

With the nozzle end of the extinguisher pointed generally upward the valve 20' is seated upon its seat and the liquid, on the inward stroke of the piston tube, enters the head 15 through the port 18 thereof, while the valve 27' of the head 16 is closed, and passes through the port 24 into the piston tube 14, as previously described, the liquid in front of the piston 31 being expelled from the pump 60

through the openings 32 and piston tube 30 as also previously described. When the piston tube 30 is again withdrawn, liquid, while the extinguisher is pointed upward, enters the head 15 through the port 18 and, while the valve 27 of the head 15 is closed, passes into the tube 22 and on into the pump, in front of the piston 31, through the ports 24' and 26' the liquid at the rear of the piston 31 being forced through the openings 33 into the piston tube 30 from which it is directed into the nozzle tube 37 as previously described. 75

While the extinguisher is held in a horizontal position and operated, the liquid may be admitted to the pump 10, on the inward 80 and outward strokes of the piston tube 30, through either of the ports 18 or 18', or both of these ports, depending upon the positions of the valves 20 and 20'. On the inward stroke of the piston tube 31, the liquid will 85 pass around valve 27 and enter the pump 10 through the port 26. During the outward stroke of the piston tube 30, the liquid passes around the valve 27' and enters the pump 10 through the port 26'. The liquid thus entering the pump 10 at opposite ends thereof is 90 expelled as previously described.

Having thus described the invention what is claimed is:

1. In a fire extinguisher, a liquid receptacle, a head having an opening through which communication with the receptacle is afforded when the extinguisher is operated, a piston-operating member projecting through said head, an operating handle slidably connected to said piston-operating member, means for locking said handle to said head, sealing means rigidly fixed to said piston-operating member and adapted, when said handle is locked to said head, to close said opening and thereby sever the communication which is afforded through said head when the extinguisher is operated, and resilient means adapted to cooperate with said handle and said piston-operating member when said handle is locked to said head to exert a longitudinal thrust upon said piston-operating member and thereby urge said sealing means into intimate engagement with said head. 105

2. In a fire extinguisher, a liquid receptacle, a head having an opening through which communication with the receptacle is afforded when the extinguisher is operated, a piston-operating member projecting through said head, an operating handle slidably connected to said piston-operating member, means for limiting relative movement between said handle and said piston-operating member, means for locking said handle to said head, a sleeve rigidly secured to said piston-operating member, a packing carried by said sleeve and adapted to be moved into engagement with said head on the inward thrust of said piston-operating member to close said opening, 110

yieldable means interposed between said piston-operating member and said handle and adapted to be placed under compression when the handle is moved with respect to said piston-operating member into its locked position.

3. In a fire extinguisher, a liquid receptacle, a head having an opening through which communication with the receptacle is afforded when the extinguisher is operated, a piston-operating member projecting through said head, an operating handle slidably connected to said piston-operating member, means for locking said handle to said head, yieldable means interposed between said handle and said piston-operating member tending to urge said piston-operating member in one direction and tending to urge said handle in an opposite direction when said handle is in its locked position, and sealing means rigid with respect to said piston-operating member and adapted to be acted upon by said yieldable means when the handle is in its locked position for closing said opening through which communication with the receptacle is afforded when the extinguisher is operated.

4. In a fire extinguisher; a liquid receptacle; a head having an opening through which communication with the receptacle is afforded when the extinguisher is operated, a piston-operated member projecting through said head; and means within said receptacle for obstructing said communication, said means comprising a retaining element surrounding said piston-operating member and having air vents formed therein and a porous material interposed between said retaining element and piston-operating member and covering said vents.

5. In a fire extinguisher; a liquid receptacle; a head having an opening through which communication with the receptacle is afforded when the extinguisher is operated; a piston-operating member projecting through said head; and means within said receptacle for obstructing said communication, said means comprising a retaining element surrounding said piston-operating member and having air vents formed therein, a ring of porous material interposed between said retaining element and said piston-operating member and covering said vents,

and a second ring of porous material surrounding said retaining element and covering said vents.

6. In a fire extinguisher, a liquid receptacle having a head, a pump arranged within said receptacle and comprising a pump tube and a reciprocating piston-operating member projecting through said head, a stripper through which said piston-operating member is adapted to reciprocate, said stripper being confined between and maintained in engagement with said head and said pump whereby said pump is held against longitudinal movement upon outward movement of said piston-operating member, said stripper being provided with a deflecting wall inclined with respect to said piston-operating member and terminating adjacent said pump in a spaced relation thereto to remove said liquid from said piston-operating member and deflect the removed liquid back into the liquid supply upon outward movement of said piston-operating member.

7. In a fire extinguisher, the combination of a liquid receptacle, an operating handle, a piston tube projecting from said receptacle into said handle and carrying said handle, a nozzle tube arranged within said piston tube, a valve slidable within said piston tube, and a spring within said piston tube adapted to cooperate with said valve for closing said nozzle tube.

8. In a fire extinguisher, the combination of a liquid receptacle, an operating handle, a piston tube projecting from said receptacle into said handle, a nozzle tube arranged within said piston tube, a valve slidable within said piston tube, and a spring within said piston tube adapted to cooperate with said valve for closing said nozzle tube, said piston tube being provided interiorly thereof at a substantial distance from its handle end with a seat adapted to engage said valve upon the outward stroke of said piston tube whereby said valve is moved out of engagement with said nozzle tube upon the outward stroke of said piston tube.

In testimony whereof, I have affixed my signature to this specification.

PETER G. MACGREGOR.
